UNITED STATES PATENT OFFICE

169,008

COMBINED COUNTER AND DESK UNIT

Howard D. Lindstrom, Marietta, Ohio, assignor
to Remington Rand Inc., New York, N. Y., a
corporation of Delaware

Application June 5, 1952, Serial No. 20,040

Term of patent 14 years

(Cl. D33—7)

To all whom it may concern:

Be it known that Howard D. Lindstrom, a citizen of the United States, residing at Marietta, in the county of Washington and State of Ohio, has invented a new, original, and ornamental Design for a Combined Counter and Desk Unit, of which the following is a specification, reference being had to the accompanying drawings, forming a part thereof.

Fig. 1 is a rear perspective of a combined counter and desk unit, showing the new design, and

Fig. 2 is a front perspective thereof.

The invention claimed is:

The ornamental design for a combined counter and desk unit, as shown.

HOWARD D. LINDSTROM.
